UNITED STATES PATENT OFFICE.

ELMER M. JONES, OF ATLANTA, GEORGIA, ASSIGNOR TO JONES SIGNAL SYSTEM COMPANY, OF ATLANTA, GEORGIA, A CORPORATION OF GEORGIA.

AUTOMATIC TRAIN-STOP.

1,129,205.

Specification of Letters Patent. Patented Feb. 23, 1915.

Application filed September 4, 1913. Serial No. 788,106.

To all whom it may concern:

Be it known that I, ELMER M. JONES, a citizen of the United States, residing at Atlanta, in the county of Fulton and State 5 of Georgia, have invented a certain new and useful Improvement in Automatic Train- Stops, of which the following is a full, clear, and exact description, reference being had to the accompanying drawings.

10 This invention relates to an automatic train stopping system where there are devices located at intervals along the trackway and adapted to coact with means on a locomotive or vehicle to give a signal or apply a 15 brake when occasion requires it. The present invention is concerned with the track devices of such system, and particularly with track devices which are adapted to invariably initiate the application of a danger 20 signal or brake, and thereafter counteract such initiation before it becomes effective if conditions ahead are clear, otherwise allowing the initiation to automatically become effective. The controlling means above 25 mentioned is claimed broadly in my prior application No. 628,832, filed May 22, 1911. The present application is concerned with means for improving the moving mechanism shown in that application; with means enabling the initiating ramp to be depressed in case of some abnormal projection from a 30 train or vehicle, and with means whereby the depression of such initiating ramp or the removal of any portion thereof, will 35 cause a signal in the rear to show danger. These and other features entering into the present invention are hereinafter more fully explained and are summarized in the claims.

In the drawings, Figure 1 is a sectional 40 side elevation of my ground device in its normal or danger position; Fig. 2 is a similar view of such mechanism in clear position, that is the position into which it automatically comes under the influence of a 45 motor and magnet when the track conditions ahead are clear; Fig. 3 is a plan of the automatic stopping device shown in Figs. 1 and 2, and Fig. 4 is an end view thereof; Fig. 5 is a vertical cross section through the sta- 50 tionary ramp and its supporting frame, as

indicated by the lines 5—5 on Fig. 2; Fig. 6 is an enlarged horizontal section on the line 6—6 of Fig. 5.

Referring to Figs. 1 to 4, 1 indicates the ties and 2 a rail of a trackway, 3 designates 55 certain ties which project farther than others, the intermediate ties 1 being shortened from the usual standard. The ties 3 are surmounted by plates 4. Bolted to these plates 4 and ties 3 is a bed plate 5, parallel 60 with the rail, for stationary and movable ramps to be described, and cross bars 6 and 7 for supporting a box 8 carrying the motor and mechanism for raising the movable ramp. 65

The normally stationary ramp consists of a pair of bars 10 and 11, hinged together by a knuckle joint at 12 and mounted at their ends between pairs of ears 13 and 14 rising from the bed plate 5. Each pair of ears carries a pin as 16 and 17, which occupy slots in the respective bars. The bars 10 and 11 are held in their normal peaked position by a pair of stiff compression springs 20, which are mounted in housings 21 secured to the 75 under side of the bed plate 5, and by members pressed upwardly by these springs against the respective bars. These members consist of plungers 23 having collars 24 resting on the springs and reduced portions extending into the springs, and heads projecting freely through the bed plate and bifurcated to extend onto opposite sides of the bars 10 and 11. Each head is preferably 80 provided with a roller 25 which bears against the under edge of the bar. By supporting the ramp bars in the manner described, I make them normally stationary, while they are depressible if necessary to allow the passage of some abnormal projection on a vehicle. An instance of such projection, I may cite the wings of a snow plow or some broken part of a train. Means hereinafter 85 described are provided for causing a danger indication if the normally stationary bars should be depressed or should become elevated above their normal position, such means being operated by one of the plungers described. 90

The movable ramp comprises a pair of 100

bars 30 and 31, connected by a knuckle joint 32. The bar 30 is a rock arm on the end of a rock shaft 33. This shaft is journaled in a bearing 34 on the bed plate 5 and a bearing 36 on the box 8. The shaft is shown as covered by a protecting sleeve 37. The ramp bar 31 has a sliding connection at its free end, with an ear 38 rising from the bed plate 5. The guide for this free end is 10 shown as consisting of two pins 39 which overhang the bar.

As explained in my prior application referred to, the stationary or danger ramp 10 and 11, the clearing or movable ramp 30, 31 15 are designed to coact with two members on the vehicle, the first of which initiates the application of a danger indication or brake, and the second of which counteracts such initiation before it becomes effective. As an 20 illustration, I may have a lever on the vehicle which rides over the stationary ramp 10, 11 and is thereby caused to open an air valve which if left alone would apply the brake and such application results if the 25 safety ramp 30, 31 is down, but if the safety ramp is up another lever on the vehicle contacts therewith and closes the valve before its open action has become effective. A suitable motor and mechanism driven thereby, 30 is provided under the control of an electric circuit to raise the safety ramp into counter-acting position when conditions ahead are clear. This motor will now be described with reference to Figs. 1 to 4 inclusive.

35 The motor and mechanism for raising the ramp bars 30 and 31 is contained in the box 8 supported by the bars 6 and 7, and normally closed by the cover 9. The motor is designated 40. It is shown as having a pinion 41 meshing with a gear 42, on the hub of which is a pinion 43 meshing with a large gear 44. On the shaft of this gear is a sprocket pinion 45 meshing with a sprocket chain 46 loose in a groove on the periphery 45 of a gear 49 journaled on a shaft 47 mounted in standard 48. Journaled on the shaft 47 is a bifurcated arm or yoke 50 in which is journaled a shaft 51. Rigid on this shaft is a sprocket pinion 52 meshing with the chain 50 46. On one end of the shaft 51 is rigidly secured a star wheel 54, adapted to be locked by a suitable pawl and magnet mechanism. When this star wheel is locked, the arm is thereby locked to the sprocket chain so that 55 the rotation of the motor may raise the arm. When the star wheel is free any movement of the motor is simply idle. Suitable mechanism, indicated by the pin 57 connects the yoke arm 50 to a rock arm 58 on the end of the rock shaft 33. Accordingly, the raising 60 of the yoke 50 raises the movable ramp to safety position.

The means for locking the star wheel 54,

comprises an electro-magnet 60 mounted on the yoke 50; an armature therefor, carried 65 by a bell crank 61, pivoted on the yoke arm 50; an arm 62 pivoted on the yoke arm and bearing against the upturned portion of the bell crank 61, and a latch bar or pawl 64 rigidly carried by the arm 62 and designed 70 to coact with teeth on the star wheel 54. The motor circuit is controlled at one point by a switch comprising the terminal 65 and the pivoted knife arm 66.

The parts are in their normal position in 75 Fig. 1. In this position a spring 67 carried by the casing engages the arm 66 and holds the motor circuit closed at this point, so that the motor is always ready to act when its circuit is closed at some other point. An 80 adjusting screw 70 rising from the base of the box, engages the bell crank 61 and holds it with the armature within range of the magnet 60. The pawl 64 is normally held in the position shown in Fig. 1, by the supporting 85 spring 72.

When circuit conditions indicate safety, the electric circuit energizes the motor and the magnet 60, these members being connected in multiple. On such energization, 90 the motor begins to rotate which starts to raise the arm 50 because the star wheel 54 is locked by the pawl 64. At the same time the magnet 60 picks its armature swinging the bell crank 61 and forcing the latch 64, 95 slightly to the right, whereupon its shoulder engages a tooth of the star wheel 54 and effectively locks the wheel so that the motor continues to raise the arm 50 thereby raising the movable ramp 30, 31, putting the automatic stop in safety or clear position. 100

As the clearing ramp comes into active position, the pawl 64 abuts a set screw 75 carried by a cross bar supported on studs 73 rising from the base and this knocks the 105 pawl 64 out of engagement with the wheel. Just preceding such action, however, the toe 78 of the lever 66 has passed the spring latch 79 and the toe catches on the latch, and another toe 80 of the lever 66 catches on a 110 shoulder on the under side of the pawl 64 wherefore the arm 50 is held elevated by the spring latch 79 as shown in Fig. 2. The releasing of the star wheel allows the whole weight of the arm to come on the toe 78 115 which swings the lever 66 on its pivot so that the motor circuit is broken between this lever and the terminal 65.

Now the parts remain in the clear position described and shown in Fig. 2, so long 120 as the magnet 60 remains energized, but as soon as that magnet loses its energization (by reason of danger conditions ahead, the breaking of a circuit, the running down of the battery or a short circuit at any point) 125 the armature lever 61 drops, releasing the

pawl 64, which releases the detent lever 66 at the shoulder 80, so that the arm 50 drops by gravity and restores the resetting ramp to normal position.

5 It should be noticed that as soon as the magnet 60 releases its armature, the lever 61 drops sufficiently to carry the armature out of range of the magnet, this being controlled by the set screw 70. Accordingly it is impossible, when the magnet once releases its armature, for it to again pick it up until the arm has dropped to its lowermost position. When it reaches that lowermost position, the spring 67 restores the lever 66 of the 15 motor circuit, and the spring 72 restores the pawl 64 and the set screw 70 lifts the bell crank 61 sufficiently so that the armature is in range of the magnet. This leaves the parts in condition ready to be picked up on 20 the succeeding energization of the motor and magnet. This requirement of the parts to go to their lowermost position after a deenergization, before they can again come to resetting position, is of importance, as it prevents the resetting arm being caused to improperly assume safety position by snow or dirt gradually packing under the arm. Such packing is a rare condition, but if it should occur, it would simply prevent the movable 25 ramps going to safety position, and thus danger would be avoided.

I have referred to the fact that one of the plungers 23 which support the normally stationary ramp is connected with means to 30 apply a danger signal in the rear in case either of the ramp bars inadvertently remains depressed from the spring supporting it giving out or from other abnormal condition, or if the ramp bar be broken or removed. This safety device is best shown in 40 Figs. 5 and 6. As appears there, a depression 90 is formed about one of the plungers 23. Against this depression bears a push rod 91 which is connected with a pivoted lever 92 forced toward the plunger by a spring 93. The spring normally keeps the push rod against the plunger. The arm 92 carries a pair of contact bridges 94 and 95, the former of which is normally in contact with two 45 terminals 96 and 97 of lines 100 and 101 leading through a battery to the relay 102, whose energization is necessary to keep the system in clear condition. The other bridging contact 95 is normally out of engagement, but may engage two terminals 105 and 50 106 of lines 107 and 108 and is thus adapted to short circuit the relay 102. Accordingly whenever the ramp bar 10 is depressed or raised or removed or broken, the plunger 23 55 is lowered or raised as the case may be, and in either case forces inward the push bar 91, swinging the arm 92 to carry the bridge contact 94 out of connection and the contact 95

into engagement, with the result that the battery line to the relay is opened and the relay is short circuited. This gives a double protection against the energization of the relay either by its own battery or any foreign current, and insures a danger indication in the rear.

70

Having thus described my invention, what I claim is:

1. In a device of the character described, the combination of a normally active ramp, a movable ramp, both ramps being adapted 75 to act on a train controlling mechanism, a motor for operating the movable ramp, a latch for holding the movable ramp in clearing position, and a magnet for controlling the movement of the movable ramp by the 80 motor and the action of the latch.

2. The combination, with a normally active ramp, of a movable clearing ramp, both ramps being adapted to act on a train controlling mechanism, a motor, gearing adapted to be driven by the motor, a movable member connected with the movable ramp, mechanism for latching the movable member to said gearing, a holding latch adapted to retain the movable member in clearing 85 position, and a magnet for controlling the latching of the movable member to the gearing and for controlling the action of the holding latch.

3. The combination, in a train signal operating device, of a motor, gearing driven thereby, a movable ramp, a bodily movable pinion connected with the ramp and meshing with the gearing, a shouldered wheel rigid with the pinion, a pawl for locking 100 said wheel, a magnet and lever for actuating said pawl, and a latching device under the control of said pawl.

4. The combination of a motor, gearing driven thereby, a movable ramp, a pinion 105 connected therewith and meshing with the gearing, a shouldered wheel rigid with the pinion, a pawl for stopping said wheel, a magnet and lever for controlling the pawl, a latch, an arm, a lever coacting with the latch 110 mounted on said arm and having a shoulder adapted to be engaged by said pawl.

5. The combination of a motor, gearing driven thereby, a movable arm, a pinion carried thereby and meshing with the gearing, a shouldered wheel rigid with the pinion, a pawl for stopping said wheel, a magnet and lever for controlling the pawl, an abutment adapted to automatically release the pawl from the shouldered wheel, and 115 latching mechanism to hold the parts when the pawl is released.

6. The combination of a motor, gearing driven thereby, a movable arm, a magnet, means under the control of the magnet for 120 locking the arm to the gearing, said means

90

95

100

105

110

115

120

125

including a pawl, a holding latch, and a switch arm adapted to engage the holding latch and be moved thereby but thereafter held by the pawl, such movement operating 5 to break the circuit to the motor.

7. The combination, with a movable signal device, of a movable arm connected therewith and adapted to be raised to move the signal device, a motor and connecting mechanism for raising the arm, a latch adapted to be engaged when the arm is raised to hold it, and a switch lever on the arm which said latch engages and swings into open position.

8. The combination, with a movable signal device, of a movable arm connected therewith and adapted to be raised to move the signal device, a motor and connecting mechanism for raising the arm, a latch adapted to be engaged when the arm is 10 raised to hold it, a switch lever on the arm which said latch engages and swings into open position, a pawl for limiting the movement of the switch lever and enabling it to act as a retaining device, and a magnet for 20 controlling said pawl.

9. The combination, with a signal device, of a raising arm for operating the same, a motor and gearing, means for latching the raising arm to the gearing to enable the 30 motor to raise the same, a pawl included in said latching means, an abutment which the pawl engages when the arm is raised, whereby the pawl is automatically withdrawn to free the arm, and a latching device for holding the arm including a switch lever on the arm which said pawl automatically engages 35 when it releases the arm.

10. The combination, with a signal device, of an arm adapted to be raised to operate the 40 device, mechanism for raising the arm including a pawl, an abutment which automatically moves the pawl to idle position when the arm reaches the top of its stroke, and means for moving the pawl to active 45 position when the arm comes to the bottom of its stroke.

11. The combination, with a signal device, of a raising arm connected therewith, a motor and operating mechanism, means for 50 latching the motor to the operating mechanism to raise the arm, means for releasing such latching means when the arm is fully raised, and means for restoring the latching means when the arm drops to its lowermost 55 position.

12. The combination, with a normally stationary ramp, of a movable ramp, a motor, mechanism operated thereby to move the movable ramp to clearing position, means 60 for automatically releasing said mechanism as the movable ramp reaches clearing position, and means for preventing connection with the motor being reestablished until the

movable ramp has returned to initial position.

65

13. The combination of a normally stationary ramp, a movable ramp, means for raising the movable ramp into peaked condition, said means including a motor, gearing and a latching device, a magnet and 70 mechanism operated thereby to latch the motor with the movable ramp, means for automatically breaking the circuit to the motor when the ramp is elevated, and means for re-establishing such circuit when the ramp 75 drops back to its down position.

14. The combination of a normally stationary ramp, a movable ramp, means for raising the movable ramp into peaked condition, said means including a motor, gearing and a latching device, a magnet and mechanism operated thereby to latch the motor with the movable ramp, means for automatically breaking the circuit to the motor when the ramp is elevated, means for 80 re-establishing such circuit when the ramp drops back to its down position, the two means last mentioned comprising a switch lever and a latching device coacting therewith on the elevated position of the device, 85 and an abutment coacting with the lever on the down position of the device.

15. The combination, with a movable ramp, of a normally stationary ramp comprising a pair of bars hinged together, 90 springs normally holding the bars in peaked position, and means for causing a danger indication when either of said bars is depressed.

16. The combination, with the bars of a normally stationary but depressible ramp, of a spring and plunger pressing upwardly on one of the bars, a member moved by the movement of said plunger, and a switch operated by said member.

100

17. The combination, with a depressible ramp, of a spring and plunger tending to hold the same elevated, a magnet, a switch for controlling the same, and means for operating said switch when the plunger is 105 either raised or lowered.

18. The combination, with a depressible ramp, of a spring, a plunger carried thereby, a switch arm connected with the plunger, a magnet and battery, a pair of switches carried by the switch arm, and circuits controlled by said switches to the magnet and battery, whereby the switch in one position closes the battery through the magnet and in the other position opens the battery line 115 and short-circuits the magnet.

19. The combination of a base, a pair of ramp bars carried thereby, a housing carried by the base, a spring in said housing, a plunger pressed upwardly by the spring 120 against one of the ramp bars and tending 125

to elevate it, a switch arm, an operating connection between the same and the plunger, and a magnet controlled by the switch arm.

20. The combination, with a base, a pair of ramp bars hinged together in a peak and mounted at their other ends on the base, a plunger, a compression spring pressing the plunger upwardly against the under side of one of the bars, a switch arm, a push rod for 10 operating the same normally occupying a

depression in the plunger, whereby the movement of the plunger in either direction moves the push rod to operate the switch.

In testimony whereof, I hereunto affix my signature in the presence of two witnesses. 15
